UNITED STATES PATENT OFFICE.

GEORGE CLAUD DEWS, OF PITTSBURG, CALIFORNIA.

TOY VEHICLE.

Application filed September 30, 1925. Serial No. 59,654.

This invention relates to improvements in toy vehicles and has for an object the provision of a vehicle in which the rider furnishes the propelling power, the mechanism being of a character to provide exercise for the rider without undue exertion.

Another object of the invention is the provision of a toy vehicle which is of novel construction, attractive appearance and which 10 requires a certain amount of skill in its operation.

With the above and other objects in view, the invention further includes the following novel features and details of construction, to be hereinafter more fully described, 15 illustrated in the accompanying drawings and pointed out in the appended claims.

In the drawings:—

Figure 1 is a side elevation of a toy vehicle constructed in accordance with the invention.

Figure 2 is a top plan view of the same.

Figure 3 is an enlarged fragmentary elevation showing a portion of the driving 25 mechanism.

Figure 4 is a section on the line 4—4 of Figure 3.

Figure 5 is a fragmentary section taken 20 transversely through the drive shaft and showing by dotted lines the ratchet teeth of the driving gear, the section being on an enlarged scale.

Figure 6 is a fragmentary elevation of a 35 portion of the driving axle.

Referring to the drawings in detail wherein like characters of reference denote corresponding parts, the reference character 10 indicates the frame of the vehicle which includes an upwardly curved front portion 40 11 which carries a steering head 12, the latter having extending from its lower end a fork 13 within which is mounted a steering wheel 14. A steering post section 15 is connected to the steering post section within 45 the steering head 12 by a universal joint 16, while at the outer end of the section 15 there are provided handle bars 17.

Extending rearwardly and included in 50 the frame 10 are spaced parallel bars 18 which carry bearing braces 19, the latter having rotatably mounted therein a driving axle 20. This axle has secured thereon a driving wheel 21 which is arranged in alignment with the steering wheel 14.

Mounted upon the frame 10 is a platform 55 22 which supports a seat 23 and the steer-

ing post section 15 is of such length as to arrange the handle bars 17 within convenient reach of the occupant of the seat.

Loosely mounted upon the driving axle 60 20 upon opposite sides of the wheel 21 are toothed segments or gears 24. These gears are engaged by racks 25 which are mounted for horizontal sliding movement in the frame 10 as indicated at 26. These racks 65 are connected by means of rods 27 with arms 28, connection being affected by links 29. The arms 28 extend downward from foot 70 pedals 30 which are mounted for pivotal movement as indicated at 31, the arms 28 being connected by a bar 32. The bar 32 is pivotally mounted as at 32' and provides for alternate opposite movement of the 75 pedals.

The segments or gears 24 are designed to 75 be locked to and released from the axle 20 by ratchet mechanisms and for this purpose each of the gears 24 is provided with teeth 33. Arranged within a slot 34 which extends longitudinally of the axle 20 is a plate whose opposite ends define dogs 35. This plate is mounted upon a pivot 36 so as to be pivotally moved longitudinally of the axle 20 and is yieldingly held against pivotal movement by oppositely arranged 80 85 springs 37.

Downward movement of the foot pedal 30 will force the rack bars 25 rearwardly and the gears 24 will be locked to the axle 20 by engagement of the dogs 35 with the teeth 90 33. Downward movement of one pedal, will move the other pedal upward and the gear of the latter will be released from the axle, the teeth 33 riding over the rounded edges 95 38 of the dogs so that the latter will move within the periphery of the axle or upon a sleeve 38 mounted thereon, due to axial pivotal movement of the plate forming the dogs. As the mechanism is duplicated upon 100 opposite sides of the driving wheel 21, a comparatively easy and even drive will be effected so that the rider will obtain a maximum amount of power for the effort involved.

The drive wheel 21 is provided with a 105 brake 40 which is connected to a pivotally mounted brake lever 41 by a brake rod 42.

Plates 43 are mounted at opposite sides of the gears 24 to keep the latter in proper 110 position with respect to the ratchet teeth 33.

The invention is susceptible of various changes in its form, proportions and minor

details of construction and the right is herein reserved to make such changes as properly fall within the scope of the appended claims.

5 Having described the invention what is claimed is:—

- 10 1. A toy vehicle comprising a body, a driving axle, supporting wheels including a driving wheel secured upon the axle, a driving gear loose upon the axle, ratchet teeth for said gear, a spring actuated dog mounted for pivotal movement longitudinally of the axle to engage the ratchet teeth and lock the gear to the axle when the gear is rotated in one direction, a foot pedal and means associating the foot pedal and gear to operate the latter.
- 15 2. A toy vehicle comprising a body, a driving axle, supporting wheels including a driving wheel secured upon the axle, a driving gear loose upon the axle, ratchet
- 20

teeth for said gear, a spring actuated plate carried by and mounted for pivotal movement longitudinally of the axle and having its opposite ends normally extended beyond the periphery of the axle to provide oppositely extending dogs for engagement with the ratchet teeth to lock the gear to the axle when the gear is rotated in one direction, a foot pedal and means operatively associating the foot pedal and gear to operate the latter.

3. In a ratchet mechanism, a shaft, a member mounted for free rotation thereon, ratchet teeth for said member and a spring actuated dog mounted for pivotal movement longitudinally of the shaft to engage the teeth and lock the member to said shaft during rotation in one direction.

In testimony whereof I affix my signature.

GEORGE CLAUD DEWS.
